APPARATUS AND METHOD FOR CONDITIONING CUT TOBACCO

Stanislaus Bogaty, Philadelphia, Pa., assignor to Proctor & Schwartz, Inc., Philadelphia, Pa., a corporation of Pennsylvania

Application December 10, 1953, Serial No. 397,399

5 Claims. (Cl. 131—136)

The present invention relates to new and useful improvements in apparatus and methods for bulking cut tobacco and more particularly to apparatus and methods for continuously processing tobacco to cool the same and obtain uniformly conditioned tobacco.

During the process of preparing tobacco, for example for use in cigarettes, the tobacco is removed from cooling cylinders at a temperature somewhat above 100° F. and at a moisture content of 12 percent. It is necessary to cool this tobacco to room temperature and equalize the moisture content therein prior to further handling. This cooling process, however, must be accomplished without forcing air or other drying medium through the tobacco since a rapid current of air will remove the aroma from the tobacco.

Prior to the present invention, the generally accepted procedure for cooling or bulking cut tobacco consisted of transferring cut tobacco from a cooling cylinder by means of a belt conveyor to a loading station where the tobacco is manually spread in bulking boxes. The bulking boxes are then transported to an air-conditioned storage room in which the air is maintained at approximately 81° F. and at approximately 60 percent relative humidity. These bulking boxes are stored in this room with a space between each box to permit a slow circulation of air between the boxes, and are maintained in the storage room for 24 to 48 hours depending upon the condition of the tobacco. After removal from the storage room the tobacco is not uniformly conditioned as the tobacco in the center of the bulking boxes will be warmer and contain more moisture than the tobacco adjacent the edge of each of the boxes. As a result of this non-uniform condition, the tobacco must be passed through a redressing cylinder to obtain a greater degree of uniformity in temperature and moisture content. In a typical installation, this above described process requires from 30 to 50 men at a cost of approximately one man hour for each 1000 to 1200 pounds of tobacco handled, and thus the labor cost of carrying out this process is relatively expensive. In addition, this system requires a considerable amount of floor space for the loading, transportation and storage of the bulking boxes.

According to the present invention, the tobacco is automatically moved back and forth continuously through an air-conditioned space and at the end of each pass through this air-conditioned space, the tobacco is dropped a substantial distance to thoroughly mix the tobacco and prevent particular portions of the tobacco from cooling or drying more rapidly than other portions of the tobacco. By this process, a considerable quantity of the tobacco is passed through the air-conditioned space at one time and each portion of the tobacco passes through essentially the same location as each other portion thereby resulting in a much improved uniformity of the final product.

With the foregoing in mind the principal object of the present invention is to provide novel automatic apparatus

2

and processes for bulking cut tobacco to obtain a uniformly conditioned tobacco.

Another object of the present invention is to provide novel apparatus and processes for bulking tobacco wherein a uniform temperature and moisture content is obtained without cooling or drying the tobacco below the desired conditions and then reconditioning the same to obtain uniformity throughout the tobacco.

10 A further object of the present invention is to provide novel automatic apparatus and processes for bulking cut tobacco wherein a relatively small amount of labor and floor space is required to carry out the process.

A still further object of the present invention is to provide novel apparatus and processes for bulking cut tobacco having the features and characteristics set forth which is highly efficient and effective in operation and use.

These and other objects of the present invention and the various features and details of the operation and construction thereof are hereinafter more fully set forth and described with reference to the accompanying drawings, in which:

Fig. 1 is a side elevational view of a bulking machine made in accordance with the present invention;

Fig. 2a is an enlarged longitudinal sectional view of the feed end of the machine illustrated in Fig. 1;

Fig. 2b is an enlarged longitudinal sectional view of the discharge end of the machine illustrated in Fig. 1.

Fig. 3 is a plan view of the feed end of the bulking machine of the present invention;

Fig. 4 is a perspective view of the conveyor and side wall construction adjacent the feed end of the bulking machine;

Fig. 5 is an enlarged fragmentary transverse sectional view taken on line 5—5, Fig. 4;

Fig. 6 is an enlarged fragmentary transverse sectional view taken on line 6—6, Fig. 4; and,

Figs. 7 and 8 are schematic views illustrating various modified conveyor arrangements for maintaining the tobacco in an air-conditioned atmosphere and effecting uniform conditioning thereof.

Referring more specifically to the drawings, reference numeral 10 designates generally a bulking machine made in accordance with the present invention comprising a housing 11 and a series of conveyors 12, 13 and 14 uniformly spaced above one another in superimposed relation. The tobacco to be processed is originally deposited in a uniform layer on the top conveyor 12 and passed through the housing 11 to the discharge end thereof wherein it is automatically discharged onto the conveyor 13 and again passed through the housing to the feed end. The tobacco then drops onto the bottom conveyor 14 and passes through the housing a third time to the discharge end of the bulking machine wherein it is discharged onto a conveyor 15 and carried to further processing apparatus (not shown).

The bulking machine may be constructed integrally with a housing and with its own air-conditioning or circulating system or, alternatively, the bulking machine 60 may be constructed without a housing and operated in a room which is suitably air-conditioned. The tobacco, when fed to the bulking machine initially has a temperature somewhat above 100° F. and a moisture content of approximately 12 percent. Before further processing, the tobacco must be cooled to room temperature while maintaining the moisture content at 12 percent, depending upon the particular requirements of the user, and uniform conditions must exist throughout the tobacco. To carry out this cooling and conditioning process, the tobacco is deposited uniformly on the upper conveyor 12 to a depth of 6 to 8 inches and is carried back and forth through the air conditioned space as described at a regulated speed

determined by the initial temperature, the desired final temperature and moisture content, and the amount of tobacco being processed. At the end of each pass through the air-conditioned space, the tobacco is dropped a substantial distance so that no one portion of the tobacco is continuously at the bottom of the layer of the tobacco and all of the tobacco will be cooled and conditioned uniformly.

The atmosphere in the housing 11 or, if no housing is used, the room in which the conveyors are mounted is maintained at a constant temperature and humidity. The temperature preferably should be approximately 81° F. while the relative humidity preferably should be approximately 60 percent.

With reference to Figs. 2a and 3, the tobacco is initially deposited on an oscillating feed conveyor 16 at the feed end of the bulking machine 10. The feed conveyor 16 is mounted in a conventional supporting frame 18 carried by a platform 21 which, in turn, is pivotally mounted for oscillating movement in a horizontal plane on an upwardly extending pedestal 22. Extending outwardly from one side of the platform 21 is a shelf or ledge 23 which mounts the drive mechanism for operating the conveyor 16 and oscillating the platform 21. This drive mechanism consists of an electric motor 24 and gear reduction box 25 which rotate a driving sprocket 26 for the feed conveyor 16 and a disc 27 for oscillating the platform 21. One end of a connecting rod 28 is pivotally secured to the periphery of the disc 27 while the other end thereof is pivotally secured to an outwardly extending arm 29 carried by the pedestal 22. Rotation of the disc 27 thereby causes oscillation of the platform 21 about the pedestal 22 and moves the discharge end of the feed conveyor 16 back and forth between opposite sides of the conveyor 12. By this construction, material placed in a hopper 31 positioned immediately above the feed end of the feed conveyor 16 will be carried out to the discharge end of the conveyor 16 and deposited therefrom uniformly over the full width of the conveyor 12.

Referring now to Figs. 4, 5 and 6 of the drawings, each conveyor 12, 13 and 14 is of conventional construction and may be either imperforate or foraminous. If an imperforate conveyor is used it may be formed of a series of articulated sections, for example as indicated at 32. The series of articulated plates 32 are carried by transversely extending girts 33 secured to laterally spaced side chains 34 which, in turn, are supported by tracks 35 extending the full length of the dryer housing 10. The side chains 34 also support traveling side guards 36 along the opposite marginal side edges of perforated plates 32 with the ends of successive guard members 36 in longitudinal overlapping relation to each other, whereby the material deposited on the conveyor is prevented from falling off of the side edges of the conveyor in transit.

A vertical stationary side guard 37 is provided at the feed end of each of the feed conveyors 12, 13 and 14 and each guard 37 has a downwardly extending lip portion 38 thereon inwardly overlying the upper ends of the traveling side guards 36 to permit a bed of material thicker than the height of the traveling side guard to be carried by each of these conveyors. Outwardly diverging stationary side guards 41 having downwardly extending lip portions 42 thereon inwardly overlying the upper edges of the traveling side guards 36, are provided for the remainder of the length of the conveyors and also prevent the material carried by the conveyor from passing over the side edges thereof.

As previously described, a uniform layer of material is deposited on the upper conveyor 12 across the full width thereof and the upper conveyor 12 is driven by means of a conventional drive mechanism, for example as illustrated at 43 in Figs. 1 and 2b, to carry the tobacco through the housing 10. As the tobacco on the conveyor 12 reaches the discharge end of the housing, it is dropped off of the conveyor 12 onto a transversely extending chute 44 and deposited thereby on the central conveyor 13 which is

driven; for example, by means of a conventional drive mechanism as illustrated at 45 in Figs. 1 and 2a, in a direction opposite to the direction of travel of the conveyor 12. The end of the conveyor 13 which initially received the tobacco extends outwardly beyond the discharge end of the conveyor 12 to receive all of the tobacco discharged from the conveyor 12. This tobacco is then carried through the housing 10 to the feed end thereof and is discharged from the conveyor 13 at the feed end of a housing onto a chute 46. The chute 46 extends transversely of the housing immediately above the feed end of the lower conveyor 14 and deposits the material uniformly across the full width of the lower conveyor 14. Drive mechanism, for example, is indicated at 47 in Fig. 2b, is provided to drive the lower conveyor 14 in a direction opposite to the direction of travel of the conveyor 13 and the end of the conveyor 14 underlying the discharge end of the conveyor 13 extends outwardly beyond the conveyor 13 to receive the material discharged therefrom. The conveyor 14 carries the material deposited thereon toward the discharge end of the housing 11 and the discharge end of the conveyor 14 is inclined upwardly to elevate the material and then deposit the same on the conveyor 15 which carries the material to further tobacco processing equipment.

In Fig. 7 there is illustrated one modified conveyor arrangement for processing tobacco in accordance with the present invention. According to this embodiment four conveyors 51, 52, 53, and 54 are provided arranged in upper and lower sets or pairs with the upper conveyors of each pair traveling in one direction and the lower conveyor of each pair traveling in the opposite direction. An oscillating feed conveyor 55, similar to the above mentioned feed conveyor 16, is actuatable between upper and lower limit positions wherein it deposits the tobacco or other material to be processed on the upper conveyor of the upper and lower pairs of conveyors, respectively.

In operation, the feed conveyor 55, for example, will first deposit a uniform layer of tobacco transversely of the conveyor 53 which travels in the direction indicated and transfers the material deposited thereon to the lower conveyor 54. After the conveyors 53 and 54 are completely covered with tobacco they stop operating and the feed conveyor is elevated from the position shown in broken lines to the position shown in full lines in Fig. 7 whereupon the material to be processed is deposited on the conveyor 51 and transferred to the conveyor 52. While the conveyors 51 and 52 are being covered by the material the conveyors 53 and 54 may remain stationary maintaining the tobacco or other material in the air-conditioned space. Prior to completely loading the conveyors 51 and 52, the conveyors 53 and 54 start operating and transfer the material deposited thereon to a transverse conveyor 56 which conveys the material to further handling apparatus (not shown). The feed conveyor is then lowered to repeat the process and the material on the conveyors 51 and 52 is transferred to a transverse conveyor 57. By this construction there is a continuous feed of material to the apparatus and a continuous removal of material from the apparatus but all of the material will remain stationary in the air-conditioned space for a predetermined period of time.

Fig. 8 illustrates a further modified conveyor arrangement for treating tobacco or other material. In this embodiment, an oscillating feed conveyor 61 similar to the feed conveyors 16 and 55 deposits a uniform layer of material transversely of a reversible inclined apron conveyor 62. The conveyor 62 first deposits the material on an upper conveyor 63 of a bank of four spaced parallel superimposed conveyors which transfers the material to a conveyor 64 at the bottom of the bank of conveyors. After these conveyors 63 and 64 are covered with the material the direction of travel of the conveyor 62 is reversed and operation of the conveyors 63 and 64 is stopped maintaining the material deposited

thereon stationary in an air-conditioned space. The conveyor 62 then deposits the material on a conveyor 65 which in turn transfers the same to a conveyor 66. Prior to the complete covering of the conveyors 65 and 66, the conveyors 63 and 64 are started thereby discharging the material deposited thereon on a transverse conveyor 67 which carries the material to further handling apparatus (not shown). Upon complete loading of the conveyors 65 and 66, the direction of travel of the conveyor 62 is reversed, repeating the above described process and the conveyors 65 and 66 will maintain the material deposited thereon stationary in the air-conditioned space and later discharge the same onto the conveyor 67. Thus, this embodiment will also maintain a continuous rate of discharge of the material being treated while permitting the material to remain stationary in an air-conditioned space for a predetermined period of time.

From the foregoing it will be observed that the present invention provides novel apparatus and processes for bulking cut tobacco to obtain a uniformly conditioned tobacco by passing the same back and forth through an air-conditioned space and at the end of each pass through the air-conditioned space, dropping the tobacco a substantial distance to permit thorough mixing thereof and obtain a uniform condition throughout the tobacco.

While particular embodiments of the present invention have been illustrated and described herein, it is not intended to limit the invention to such a disclosure and changes and modifications may be incorporated and embodied therein within the scope of the following claims.

I claim:

1. In apparatus for bulking cut tobacco and similar material comprising, a supporting structure, a conveyor system carried by said supporting structure including a plurality of spaced superimposed conveyors, feed mechanism including a reversible feed conveyor operable in one direction to deposit material on one of said conveyors and in the other direction to deposit material on another of said conveyors, drive means to drive said one and said another conveyors in one direction, a chute extending transversely of said supporting structure adjacent said one conveyor operable to receive material therefrom and transfer the same to a third of said conveyors, a second chute extending transversely of said supporting structure adjacent said another conveyor operable to receive material therefrom and deposit the same on a fourth of said conveyors, drive means to drive said third and said fourth conveyors in a direction opposite to the direction of travel of said one conveyor, and means to remove material from said third and fourth conveyors.

2. In apparatus for bulking cut tobacco and similar material comprising, a supporting structure, means to maintain the atmosphere about said supporting structure at a predetermined temperature and humidity, a conveyor system carried by supporting structure comprising similar upper and lower pairs of superimposed conveyors, drive means operable to drive the conveyors of each pair in opposite directions, a feed conveyor, means operable to raise and lower said feed conveyor between upper and lower limit positions adjacent the upper conveyor of said upper and lower pairs of conveyors respectively, said feed conveyor operable in the upper limit position to feed material to the upper pair of conveyors and in the lower limit position to feed material to the lower pair of conveyors, means to transfer material from the upper conveyor of each pair to the lower conveyor of each pair to thereby convey the material back and forth through the air-conditioned space, and means to remove the material from the lower conveyor of each pair of conveyors.

3. In the method of cooling and conditioning cut tobacco the steps which comprise, forming a uniform layer of tobacco of substantial depth on a pair of superposed conveyor runs mounted in an air-conditioned space by depositing tobacco continuously on the upper of said runs during movement of said run in one direction while the underlying run moves in the opposite direction until said runs have received a uniformly deposited bed of tobacco of substantial depth by reason of such deposit and their movement, thereafter forming a uniform layer of tobacco of substantial depth on a second pair of superposed conveyor runs mounted in said air-conditioned space by depositing tobacco continuously on the upper of said runs during movement of said runs in one direction while the underlying run moves in the opposite direction until said runs have received a uniformly deposited bed of tobacco of substantial depth by reason of such deposit and their movement, the movement of the second pair of conveyor runs being accomplished while the first pair of conveyor runs with their deposited bed of tobacco are stationary and the movement of the first pair of conveyor runs being accomplished while the second pair of conveyor runs with their deposited bed of tobacco are stationary, and delivering tobacco from said air-conditioned space from the moving pairs of conveyor runs on which it has been deposited.

4. In apparatus for bulking cut tobacco, a conveyor system comprising a pair of vertically spaced conveyors having horizontally extending conveyor runs in overlapping relationship mounted to receive and transport successively tobacco deposited on the upper of said conveyors, means for simultaneously driving said conveyor runs in opposite directions intermittently, a second pair of vertically spaced conveyors also having horizontally extending conveyor runs in overlapping relationship mounted to receive and transport successively tobacco deposited on the upper conveyor of said second set, means for simultaneously driving said second set of conveyor runs in opposite directions intermittently during the interval when said first set of conveyors are idle, and means for feeding tobacco alternately to the upper conveyor of each of said sets while it is being driven, whereby tobacco fed to each of said conveyor sets is held thereon first during a feeding cycle and then during an idling cycle of that set.

5. In apparatus for bulking tobacco and the like, the combination comprising an endless conveyor having a horizontal conveying run adapted to support a body of tobacco, side guards attached to said endless conveyor and extending upwardly from said conveying run, and stationary side guards inwardly overlapping at their lower ends said conveyor-attached side guards and extending upwardly therebeyond, said upward extensions projecting substantially vertically from their overlapped relation to said conveyor-attached side guards adjacent the tobacco-receiving end of said conveyor but diverging outwardly therebeyond to provide a pocket adjacent the upper portion of the body of tobacco impelled forwardly upon said conveyor.
